TENNIS TABLE

Leo B. Gatz, Chicago, Ill.

Application September 15, 1938, Serial No. 230,134

1 Claim. (Cl. 311—35)

My invention relates to tables for playing ping pong or miniature tennis games in the home, and my main object is to provide a table for this purpose which is easily put together or taken apart.

5 A further object of the invention is to provide a table of the above character which becomes rigid and upright when set up, so as to have stability.

Another object of the invention is to provide 10 means whereby the table will square itself and otherwise become adjusted to uneven surfaces, so as to present a stable structure and even top.

Another object of the invention is to provide a 15 construction between the table top and the supporting structure therefor which will cause the top to become properly centered, aligned and fitted in relation to the supporting structure.

An additional object of the invention is to construct the supporting structure of the table with 20 a peculiar and highly efficient assembly formation, whereby to combine alignment, strength, adjustability and compactness.

Another object of the invention is to include in 25 the novel table simple and adjustable means for supporting the net over the same.

An important object of the invention is to design the novel invention along lines of neatness and utmost simplicity, in order that it may present a good appearance and be economical to 30 produce.

With the above objects in view, and any others which may suggest themselves from the description to follow, a better understanding of the invention may be had by reference to the accompanying drawing, in which—

35 Fig. 1 is an elevation of the novel table in the assembled form;

Fig. 2 is a bottom view;

40 Fig. 3 is a fragmental perspective view of portions of the table in separated relation; and

Fig. 4 is a detailed section on the line 4—4 of Fig. 2.

In the development of apparatus for games in the miniature for indoor use, it is essential that 45 the apparatus be of a nature to be simple, easily handled and inexpensive. Thus, a table for ping pong or indoor tennis, while of considerable size, must be made in sections in order to be easily handled or compactly stored, and it has therefore 50 been my intention to so design a table of this kind that it may present as many advantages as possible.

In accordance with the foregoing, the novel 55 table is designed with two major units, that is, the top and an understructure to support the

same. Thus, the top is divided at the center as indicated at 10 to form adjoining sections 11 and 12. Each of the sections has lateral skirt sections 13 connecting with a terminal skirt section 14; also, the underside of each section receives blocks 15 inwardly of the skirt portions 13 and blocks 16 similarly related to the skirt portion 14. Each section also has a crossbar 17 on the underside a short distance from the inner edge. One section has a block 18 on the underside at the center, the block extending inwardly from the related crossbar 17, while the other section has three such blocks 19 in spaced relation and similarly located in respect to the corresponding crossbar. The length of the blocks 18 and 19 is such that they extend beyond the section carrying them to underlie the adjacent edge of the adjoining section when the table sections are assembled as Fig. 2; and the medial block 19 is in staggered relation to the block 18.

10 The unit for supporting the table top is generally in the form of an oblong frame with legs at the corners. Thus, the frame is composed of side rails 25 and end rails 26, the latter receiving the legs 27 along their inner sides at the extremities of the rails. The legs are glued or otherwise rigidly fastened to the end rails 26, while the side rails 25 are formed separately from the end structures, as clearly shown in Fig. 3.

15 In order that the side rails may be assembled with the end structures for the formation of the understructure, the legs 27 are formed with side brackets 28 presenting upward tongues 29 in spaced relation to the legs and adjacent terminal edges of the end rails 26. The vertical slots 30 thus formed are calculated to provide a smooth 20 sliding fit for the end portions of the rails 25 when these are deposited in the brackets 28. Such end portions also carry pairs of spaced and outwardly extended lugs 31. The contiguous faces of these 25 are flared downwardly to form a tapered slot 32 in each instance. The tongue 29 has its end faces 33 tapered upwardly, so as to form a joint with the lugs 31 when the corresponding end portion of a side rail 25 is assembled with the end structure 26 in the manner indicated in Fig. 1. The understructure is thus formed, requiring no 30 nails or other fastening means or the use of force or tools of any kind.

25 In the application of the table top to the understructure, it is only necessary to place the top sections in the usual position over the frame underneath, the lugs 15 and 16 of the top serving to space the same properly from the sides and ends of the frame by abutting the latter as indi- 35

cated in Fig. 2. The bars 17 of the top are somewhat shorter than the spacing of the side rails 25, so as to freely assume the position of spacers for these and supplement the blocks 15 in the alignment of the top with the sub-frame.

It is customary to place standards at the sides of the table for the suspension of a net across the center thereof. For the present purpose the standards are in the form of metal strips 35 having inward bottom bends 36. In order that these standards may be applied to the novel table, the skirt portions 13 thereof are horizontally slotted as indicated at 40 on both sides of their central meeting line, so that the bends 36 of the standards may be inserted through the slots. Each base portion 36 extends over a bracket 37 carried by the top section 11, the free end of the bracket underlying a lug 38 carried by the section 12. The bracket is either of metal or has a metal insert through which is threaded a bolt 39. Thus, after the standards 35 have been placed and adjusted for the proper suspension of the net (not shown), the bolts 39 may be tightened to render the net support rigid.

It will be evident from the above description that I have provided a tennis table which is in two major units, these being easily separable and the supporting unit so taken apart that a compact bundle of the table may be made for storing, packing or shipping the same; yet when the table has been set up as described, the rigid end supports are firmly united with and by the side rails, so as to form a stable and firm understructure. The taper-joints formed at the corner assure properly squared-up relation of the understructure; yet, the nature of the joints permits a slide adjustment in any of them to allow for an uneven part of the floor or other supporting surface without affecting the support of the table top sections. The ample area over which these extend, as well as the plurality of points of alignment between the top and the

understructure, furnish an even support for the top sections. It is significant that no nails or other fastening means are required to assemble the table, and that the work may be done by anyone easily and quickly, since no skill, undue effort or tools of any kind are required. Also, it is an easy matter to raise the top sections and take apart the frame underneath when the table is to be put away, making the same handy in this respect. Constructed along the lines described, it is not necessary to use heavy or massive parts for the table, and the latter may thus be made light without sacrificing strength. Finally, it is evident that few parts enter into the construction of the novel table, rendering the same inexpensive to produce.

While I have described the invention along specific lines, various minor changes and refinements may be made without departing from the principles of the invention, and I desire to consider all such changes and refinements as coming within the scope and spirit of the appended claim.

I claim:

An understructure for table tops or the like, comprising a pair of end units and a pair of side rails adapted to connect the same, each end unit being composed of an end rail having a leg integrally attached to each end thereof and an outwardly offset bracket integrally carried by an outer surface of each leg adjacent the top thereof, each bracket providing an upwardly opening vertical slot between the inner surface thereof and the outer surface of said leg, an end portion of a side rail being adapted to be received in each slot, spaced lugs on the outer surface of each end portion of each side rail, the facing surfaces of said spaced lugs being adapted to bear against opposite side edges of its bracket to prevent longitudinal displacement of said side rail in said slot.

LEO B. GATZ.
